(57) **CLAIM**

The ornamental design for a fabric with camouflage pattern, as shown and described.

DESCRIPTION

The patent or application file contains at least one drawing executed in color. Copies of this patent or patent application publication with color drawing will be provided by the Office upon request and payment of the necessary fee. The sole FIGURE is a plan view of a fabric with camouflage pattern.

The broken lines surrounding the FIGURE denote the boundaries of the claim and form no part thereof.
